KNITTING MACHINE

Charles W. Strzalkowski, Milwaukee, Wis.

Application December 14, 1938, Serial No. 245,616

9 Claims. (CL. 66—82)

My invention relates to improvements in knitting machines, with particular reference to multiple section flat knitting machines, such as are employed for knitting full-fashioned hosiery. The term "section" is herein used to define a complete assembly of needles and operating equipment employed for knitting a single blank. The number of sections in the machine corresponds to the number of blanks to be simultaneously knitted—all of the sections being normally actuated from a common source of power.

The object of my invention is to provide means for rendering any individual needle bar temporarily inoperative for the purpose of repairing or replacing needles while allowing the remainder of the machine to continue in normal operation.

The needle bars of flat knitting machines must be operated with precision, and the operating mechanism is factory predetermined as to position with reference to the oscillatory shaft or rock shaft from which all the needle bars in the machine are raised and lowered in timed relation to other normal operations of the machine.

It is therefore a specific object to provide means whereby any given needle bar may be temporarily brought to rest without disturbing the relationship of its operating mechanism to the main rock shaft from which all of the other needle bars are being raised and lowered.

A further object of my invention is to provide means whereby any needle bar which is temporarily brought to rest may preserve its relationship to the operating mechanism so completely as to allow instant restoration to operating condition.

A more specific object is to provide a flat knitting machine with a set of longitudinally divided bars, one section of which may serve as a supporting portion in permanently fixed relation to the operating mechanism, whereas the needle carrying portion or needle bar may be wholly or partially separated, but capable of precise restoration to a factory predetermined relationship with its supporting or operating section.

A further object is to provide means whereby the needle bars of a flat knitting machine may be normally latched to the operating mechanism and brought to rest only after a manual release of the latches; to provide means whereby such a needle bar may be instantly brought to rest after release of the latches and without any cessation in the operation of the other parts of the machine; to provide means whereby each needle bar, when brought to rest or preparatory to being

brought to rest, may be adjusted out of its normal relationship to the sinker head, and then supported in a stationary position independently of its individual operating mechanism, the latter being continued in operation as above stated.

In the drawing:

Figure 1 is an elevation of one section of a flat knitting machine, showing the needle bar operating shafts in cross section, and with dotted lines illustrating the needle bar and its supporting lever in an inoperative position.

Figure 2 is a plan view of the same showing fragments of adjacent needle bar sections.

Figure 3 is a detail showing one of the needle bars and a fragment of its supporting lever in elevation.

Figure 4 is a detail view taken at right angles to Figure 3 and showing the needle bar and cross head in cross section, exposing one of the dowel pins.

Figure 5 is a view similar to Figure 1, with the inoperative needle bar and its support illustrated in full or solid lines, and with parts broken away to show a modified form of construction.

Figure 6 is a fragmentary view of a modified form of needle bar, a fragment of the supporting lever being illustrated, and the associated rocker arm being illustrated in section.

Like parts are identified by the same reference characters throughout the several views.

Knitting machines of the described type are made in multiple sections, each equipped with at least one needle bar and an oscillatory actuator mechanism to reciprocate the needle bar for normal knitting operations. The actuator includes a rock shaft having lifting arms from which the normal reciprocatory movements are derived, and a needle bar supporting lever, sometimes called a "press lever," is pivoted to each of these arms and transmits its motion to the needle bar. An associated rock shaft is equipped with press arms normally linked to the lower ends of the press levers, the linkage being manually adjustable to swing the levers into and out of operating knitting positions. Heretofore it has been necessary to stop the entire machine in order to remove and replace needles or to remove a needle bar, and so far as I am aware, machines in commercial use are not operated while such repairs are being made, although attempts have been made to provide means whereby a machine can be stopped, a needle bar removed and the machine then continued in operation until it is again stopped to permit replacement of the bar. I believe such attempts have not been successful, due

50 to provide means whereby a machine can be stopped, a needle bar removed and the machine then continued in operation until it is again stopped to permit replacement of the bar. I believe such attempts have not been successful, due

to the difficulty of restoring the needle bar precisely to its original position, and also to the inconvenience resulting from a stoppage of the machine for two periods of perhaps longer duration than that required for the repair and replacement of needles while the entire machine is at rest. My improved construction provides means for arresting the movement of any given needle bar while the remainder of the machine continues in operation, including the actuator mechanism for that particular needle bar.

In Figure 1, the rocker shaft 10, arm 11, press shaft 12, its arm 13, link bar 14, needle bar supporting lever 15, the needle bar members 16 and 17, and the work table 18 may all be of ordinary construction, except as hereinafter described. The needle bar member 16 may be conveniently termed the needle bar body. It is mounted upon a cross head 20 carried by the upper end of the lever 15 in the illustrated embodiment.

The cross head 20 is integrally connected with the lever 15, and is apertured near its respective ends to receive dowel pins 22 carried by the body 16. Between the dowel pins and the supporting lever 15 the cross head is provided with depending brackets 23. Above the brackets the cross head is apertured to receive coiled tension springs 24, each spring being connected at its upper end to the body 16 of the needle bar. Its lower end is connected with the associated bracket 23.

In this embodiment the springs 24 constitute a permanent resilient connection between the cross head and the needle bar body 16, and the dowel pins 22 are of sufficient length to maintain the relationship of the needle bar to its operating mechanism within a limited range of separation between the needle bar and the top of the cross head.

At each end of the needle bar body 16 it is provided with an axially projecting stud 27. The work table 18 is provided with depending brackets having rearwardly projecting arms 28, the extremities of which have hook-shaped sockets 37 in their upper surfaces in which the studs 27 may be engaged. Such engagement may be brought about by manipulating the link 14 to push the lower end of the lever 15 rearwardly when the lifting arm 11 is at the upper end of its stroke. The extremities of the bracket arms 28 are inclined or rounded beyond the sockets 37, whereby the studs 27 may ride upon these inclined or rounded surfaces when moving toward engagement in the sockets. The needle bar body 16 may be locked to the cross head 20 by set screws 39 to avoid any tendency of the springs 24 to yield and allow the parts 16 and 20 to slightly separate when their motion reverses at the upper end of their stroke. These set screws, if used, will be retracted from their engagement with the dowel pins 22 before engagement of the studs 27 in the sockets 37.

When the studs 27 are thus engaged in the sockets 37 the needle bar will be held against downward movement, although the arm 11, the lever 15 and cross head 20, may be moved downwardly and upwardly in correspondence with the oscillations of the shaft 10. During the downward stroke, the cross head 20 will draw away from the needle bar body 16, but the relationship of these parts will otherwise be maintained by the distending springs 24 and the sliding engagement of the dowel pins 22. As shown in Figure 4, the dowel pins 22 are preferably in a vertical position when the body 16 of the needle bar is engaged with the bracket arms 28.

Therefore, at the end of each upward stroke of the arm 11 the cross head 20 will be restored to its normal relationship to the body 16 of the needle bar, and at that time the link 14 may be again manipulated to pull the lower end of the lever 15 forwardly and restore the needle bar to its normal knitting position.

While the studs 27 are engaged with the table brackets, needles may be removed and replaced freely, the needle bar being substantially in a stationary position. All other sections of the knitting machine may be continued in operation, and knitting operations will be suspended only in the particular section where the needle bar has been adjusted out of knitting position and into engagement with the bracket arms 28. After the needles have been repaired or replaced, the release of the needle bar and its restoration to operative position can be made without loss of time and without suspending the operation of the knitting machine.

In Figure 5 I have illustrated a modification in which the needle bar supporting lever 15a is formed integrally with the needle bar body 16a in accordance with common practice as heretofore followed. The needle bar body 16a serves also as the cross head for the lever, but for the purposes of my invention I provide the ends of the bar with fingers 27a, engageable with sockets 37a in the bracket arms 28a. The lower end of the lever 15a is provided with a foot piece 40, having a rounded socket at 41 to receive a resilient stud or latch knob 42 carried by the frame member 43. When the lower end of the lever is engaged with the stud 42, and when the fingers 27a on the needle bar are engaged with the bracket arms 28a, both the lever and the needle bar will be held in a stationary position.

To permit the operating arm 11a to continue its oscillation, I resiliently connect it with the needle bar support or press lever 15a by a tension spring 24a. The extremity of the arm 11a carries a head which has the form of a slide 45 which is rectangular in cross section and adapted to swing in a slot 46 in the lever 15a, the head having a sliding fit in said slot. The slide has a cylindrically rounded top, and at the upper end of its stroke, this top portion enters a semi-cylindrical socket 48 at the upper end of the slot 46.

The spring 24a in Figure 5, and the corresponding springs 24 shown in Figure 3, have sufficient residual tension when contracted to hold together under normal knitting conditions the parts which they connect. The inertia of the needle bar and the friction of the needles upon the stationary press bar or sinker head 49 is insufficient to overcome the tension of the springs, even when contracted, and therefore the needle bar and its operating connections are substantially operated as an integral unit, except when the needle bar is hooked to the work table.

In the embodiment shown in Figure 5, the needle bar oscillating arm 11a is shown in its depressed position, i. e., at the lower end of its oscillatory stroke. When it returns to the upper end of its stroke the top of the slide is in the socket 48, and if the link bar 14a is then pulled forwardly the latch knob 42 will be pushed downwardly against the tension of its actuating spring to release the lower end of the needle bar supporting lever 15a, whereupon the fingers 37a will be withdrawn from their supporting hooks 28a, the needle bar supporting lever swinging pivotally upon the cylindrical top of the slide 45.

until the link notch 50 may receive the stud 32a on the cam actuated press arm 13a.

All of the parts may thus be restored to normal operating or knitting position without any stoppage of the knitting machine to permit such restoration.

In Figure 6, I have illustrated a modified form of needle bar and cross head. At each end of the body 16b of the needle bar I provide dowel pins 22b adapted to enter a registering aperture in the cross head 20b. These dowel pins 22b, and the corresponding dowel pins 22 used in the embodiment illustrated in Figures 1 to 4, inclusive, may be keyed to the cross head either by set screws indicated at 39 in Figure 3, or by latch keys 56 illustrated in Figure 6. The latch keys 56 are preferred, and will therefore be here described in detail. They are adaptable to any form of needle bar having an adjustable relation to the cross head in which dowel pins or equivalent guides are employed to maintain the relationship of the adjustable parts.

In Figure 6, the dowel pins are provided with sockets or arcuate channels in which latch keys 56 are adapted to fit. These keys are each mounted in an axial bore in the end of the cross head, the outer end of which is closed by an axially slotted nut 57 through which a key operating rod 58 extends and is provided with an exterior knob 59. The rod 58 has a cross pin 60, movable longitudinally in the nut 57 along the slot therein. A compression spring is interposed between the nut 57 and the key 56 to hold the key normally in engagement with its associated dowel pin 22b. The key 56 can be retracted until the cross pin 60 is withdrawn from the nut 57. Thereupon the knob can be rotated until the cross pin 60 spans the slot in the nut 57 and thus locks the key in the retracted position.

With this construction, all of the parts except the needle bar and cross head may be of any ordinary construction, in which a link 14 may be adjusted to swing the press lever to an inoperative position, with the needle bar adjusted forwardly in the direction of the work table, as illustrated by dotted lines in Figure 1. Thereupon, while the needle bar supporting lever and needle bar are still being oscillated by the arm 11, the knobs 59 at the respective ends of the cross head may be retracted to withdraw and lock the keys 56 in retracted position. The needle bar may then be lifted from the cross head and carried to any suitable point or table for the repair and replacement of needles. Upon completion of this work the needle bar may be returned and placed in position upon the oscillating cross head, the dowel pins 22b guiding the bar to its correct position, in which it may then be locked by the keys 56.

In each of the three embodiments illustrated it is unnecessary to stop the knitting machine. Any one or more of the needle bars may be withdrawn from operating position and held either in fixed relation to the work table or upon any other support if the modification illustrated in Figure 6 is employed. Restoration to operative position of the repaired needle bars is likewise effected without interruption in the operation of the other parts of the knitting machine, and no displacement or disalignment of the needle bar operating mechanism is possible, particularly in the matter of precision in the relationship of the needle bar to the relatively fixed sinker head 49.

It will be understood that the tension springs 24 (Figure 3) and the corresponding spring 24a

(Figure 5) have sufficient normal tension to hold the parts which they connect fixedly together under the stresses of a normal knitting operation. It is only when the needle bar and needle bar supporting lever are out of normal knitting position, and the needle bar held against movement, that the springs will be distended to allow the actuating arm 11 (or 11a) to continue to oscillate, and to also allow the needle bar supporting lever to continue to oscillate when the springs are employed to connect the needle bar with the needle bar supporting lever or its cross head.

It will be observed, in Figure 4, that the dowel pins 22 occupy substantially a vertical position when the needle bar body is in engagement with the brackets 28, the needle bar supporting lever then occupying an inclined or abnormal position, in which it moves bodily along substantially vertical lines, from which it deviates only slightly in correspondence with the short arc in which the end of the arm 11 swings. This slight arcuate movement is, of course, transferred to the needle bar supporting lever and the needle bar, but it is negligible, and therefore the needle bar is held by the hooks 28 in a substantially fixed position while the needles are being repaired or replaced.

I claim:

1. In a multiple section flat knitting machine having each section equipped with a needle bar and an associated oscillatory actuating arm therefor movable in a vertical plane each section including all of the needles employed for completing a single fabricated blank, the combination therewith of connections for normally transmitting the motion of the arm to the needle bar, and means operable when the needle bar is at the upper end of its stroke for engaging it with a fixed support out of its normal path of reciprocation, said connections being adapted to yield sufficiently to allow continued oscillation of the arm while the movement of the needle bar is arrested, and said connections including dowelling means adapted, when the needle bar is released, to precisely guide the needle bar to its original operative relation to the actuating arm, whereby any given needle bar may be brought to rest, its needles repaired or replaced and the bar restored to operative position without delaying the operation of the other sections.
2. In a machine of the described class, the combination of separate needle bar mountings, means for normally reciprocating the mountings in unison, a needle bar carried by each mounting in factory predetermined relation thereto and provided with a complete set of needles for knitting a single fabricated blank, a relatively fixed support, means for engaging the needle bar with said support when at the limit of its reciprocating stroke in one direction, connections adapted to allow the mounting to continue to reciprocate when the needle bar is so engaged, and means for guiding the needle bar to its normal operative position on the mounting when released from said support.
3. In a multiple section flat knitting machine provided with individual oscillatory actuators and associated needle bars, each needle bar having a complete set of needles for knitting a single fabricated blank and each actuator including a needle bar supporting cross head with which the needle bar has sliding dowelling connection, springs normally holding the needle bar to the cross head, said cross head and its associated needle bar being movable out of its normal path of oscillation, and a relatively fixed support en-

gageable by the needle bar when the cross head is out of its normal path of oscillation, said dowelling connections being of sufficient length to allow the crosshead to reciprocate while in sliding connection with the stationary needle bar, said connections being adapted to guide the needle bar to its normal position on the cross head when released from the fixed support.

4. In a multiple section flat knitting machine having each section equipped with a needle support equipped with all the needles required for a single fabricated blank, and an associated oscillatory actuator, the combination, with each needle support, of resilient means for maintaining a yielding connection between the needle support and the actuator while the needle support is at rest and the actuator in motion, means for holding the needle support at rest out of the path of normal reciprocation, and mechanical means for guiding the needle support into normal relationship to the actuator when released from said holding means.

5. In a machine of the described class, a reciprocatory needle bar mounting, a needle bar normally carried by the mounting in factory predetermined relationship thereto, means for continuously reciprocating the mounting, latch means normally locking the mounting to the needle bar and means, operable while the machine is in motion, for releasing the needle bar from said latch means and supporting it out of knitting position while the machine is in operation.

6. In a machine of the described class, a reciprocatory needle bar support, a needle bar provided with a complete set of needles for knitting a single fabricated blank and normally carried by the support in factory predetermined relationship thereto, a fixed support with which the needle bar may be temporarily engaged for repair and replacement of needles while its actuating mechanism and all other portions of the machine are in continuous operation, dowelling means for ensuring a return of the needle bar to its support in precise factory predetermined position, said needle bar being removable and replaceable without material loss of time in the operation of the other portions of the machine, and manually releasable latch means for normally holding the needle bar to the support.

7. A flat knitting machine having multiple sec- 50

tions, each equipped with a single needle bar and needles for knitting a complete fabricated blank, power driven actuating means for normally reciprocating the needle bar in all of the sections to simultaneously fabricate a set of blanks corresponding to the number of sections, latching means retractible while the machine is in operation for releasing the needle bar in any one section, and means for supporting the released bar in a stationary position while blanks are being completed in other sections.

8. A flat knitting machine having multiple sections, each equipped with a single needle bar and set of needles for completing a single fabricated blank, power driven means for simultaneously actuating the needle bars of all the sets to complete a number of blanks corresponding to the number of sections, means for arresting the movement of the needle bar in any one of the sections and holding it in a stationary position while its actuating mechanism continues to reciprocate while those of the other sections are in substantially continuous operation, and means, operable without material loss of time in the operation of the machine, for restoring the arrested needle bar to factory predetermined relationship with the actuating mechanism preparatory to fabricating the next set of blanks, whereby the knitting of any one blank may be interrupted without material loss of time in the fabrication of the other blanks and in the fabrication of successive sets of blanks.

9. In a multiple section flat knitting machine, the combination of an oscillatory operating shaft common to all of the sections and provided with a permanently attached needle operating member for each section, a needle support for each section in factory predetermined relationship to the operating member and normally locked thereto, said support being equipped with all the needles required for completing a single fabricated blank, momentarily operable means for unlocking and re-locking said support, and means for holding said support in a fixed position pending complete fabrication of blanks in the other sections, whereby needles in any given section may be repaired or replaced while the blanks in the other section are being completed.

CHARLES W. STRZALKOWSKI.
